CLAIM

The ornamental design for a mirror, as shown and described.

DESCRIPTION

FIG. 1 is a front elevational view of a mirror showing my new design;

FIG. 2 is a cross-section taken along line 2—2 of FIG. 1;

FIG. 3 is a top plan view thereof;

FIG. 4 is a bottom plan view thereof;

FIG. 5 is a right side elevational view thereof, the opposite side being a mirror image; and

FIG. 6 is a rear elevational view thereof.
